UNITED STATES PATENT OFFICE.

JOHN F. TEEHAN, OF BROCKTON, MASSACHUSETTS.

SHOE AND PROCESS OF MAKING THE SAME.

1,393,730.

Specification of Letters Patent. Patented Oct. 11, 1921.

Application filed April 12, 1920. Serial No. 373,073.

To all whom it may concern:

Be it known that I, JOHN F. TEEHAN, a citizen of the United States, residing at Brockton, in the county of Plymouth and State of Massachusetts, have invented new and useful Improvements in Shoes and Processes of Making the Same, of which the following is a specification.

The object of the present invention is to produce a flexible and comfortable shoe and also an improved innersole for use therein, as well as the method of manufacturing the same.

In accordance with the present invention, the innersole is formed with a continuous rib or lip extending from the heel end on one side entirely around the forepart of the shoe to the heel end on the other side, to which a continuous or uninterrupted welt 20 may be attached in the usual welt-sewing or inseam operation, the innersole itself being split so as to provide two layers or members at the shank of the shoe, as a result of which the shoe is highly flexible at the shank. In 25 preparing the innersole, which is made of leather or an equivalent material, I preferably first form and turn the rib or lip which follows the contour of the sole around the shank and forepart, and then, by a suitable 30 instrumentality, the sole is split, preferably in a plane at the base of the rib, so that, while the innersole is thus formed into two layers, the rib on the upper layer is integral with and a continuation of the rib on the 35 unsplit portion of the innersole. A very decided advantage is secured by this procedure, when the welt and upper are sewed to the innersole, since the reentrant angle or corner formed by the rib and the upper 40 face of the sole, which is engaged by the guide of the welt-sewing machine, is continuous, uninterrupted and unobstructed, and the shoe can be fed smoothly in relation to the sewing mechanism in forming the in- 45 seam from heel to heel of the shoe. The innersole may be split from either end, so as to form the two integrally connected layers at the shank, between the heel and the forepart of the sole, but for usual purposes 50 it is preferable to split the innersole from the heel end. The two layers of the innersole are preferably permanently connected together at the heel end of the shoe when the shoe is finished. This may be accom- 55 plished by securing the heel ends of the lay-

ers together by suitable fastening means before the innersole is secured to the upper and the welt by the inseaming operation, or, if desired, the said ends may be secured together by the tacks and the heel nails in 60 securing the upper and heel to the shoe at the heel end thereof.

Obviously the entire under face of the innersole may be reinforced with a layer of textile material from toe to heel, the margin 65 of which is upturned in the channeling operation to form a part of the up-turned rib or lip. This is sometimes desirable where the innersole is formed of relatively soft or spongy leather or of leatherboard. 70

When the shoe is completely formed, the shank of the innersole consists of two separate layers or members integrally connected at one or both ends, but capable of separation in the act of flexing the shoe, so that the 75 shoe itself is very flexible at the shank, the upper layer curving upwardly between its ends and bearing against the arch of the foot. Since there is a relative movement of the two layers or members of the inner- 80 sole, when the wearer of the shoe is in the act of walking, and consequently there may be a tendency of the shoe to "squeak", such squeaking may be obviated by placing a layer of fibrous or other suitable material 85 between the shank members. For example, a piece of thin canvas or other cloth may be connected to the inner face of one of the members.

On the accompanying drawings,— 90

Figure 1 shows a channeled innersole with the lip or rib turned.

Figs. 2 and 3 represent sections through the same on the lines 2—2 and 3—3, of Fig. 1. 95

Fig. 4 is a plan view of the innersole as split from the heel end.

Fig. 5 represents a section on the line 5—5 of Fig. 4.

Fig. 6 represents a longitudinal section 100 through the innersole after the inner face of the rib-carrying shank member has been covered with a fabric layer.

Fig. 7 represents a section on the line 7—7 of Fig. 6. 105

Fig. 8 represents a partially formed shoe, in which the upper and welt have been inseamed to the rib on the innersole.

Fig. 9 represents a side elevation, partially in section, of a shoe embodying the present 110

invention and illustrates the separation of the shank members of the innersole when the shoe is flexed.

Figs. 10 and 11 respectively represent enlarged sections on the lines 10—10 and 11—11 of Fig. 9.

In preparing the innersole, indicated as a whole at 20, I use some suitable stock such as leather, leather-board, or their equivalent, which is capable of being split, and may, if desired, cover the upper face thereof with a sheet 21 of fabric cemented in place. For this purpose, a "frictioned" fabric may be employed. Then, by a channeling machine of suitable design, a channel 23 is formed in the side edge of the sole, and a lip or rib 22 is upturned, from the point *a* at the heel end entirely around the shank and forepart to the point *b* at the heel end, as shown in Fig. 2.

Then, by a splitting machine, *e. g.* one having a band knife, the innersole is split from the extremity of the heel end, through the shank to a transverse line *c—c* substantially coinciding with the "break" of the shoe, or slightly beyond what might be termed the toe end of the shank. This operation divides the heel and shank portion of the innersole into two members 25, 26, which are integrally connected at their forward ends, the plane of division being coincident with the plane of the face of the feather 24 or at the base of the rib or lip. As a result, the rib or lip 22 is formed partially on the unsplit forepart and partially on the shank member 26, and constitutes, as it were, the upturned marginal edge of the said shank member.

If desired, the member 26 may be folded over the forepart of the innersole, and the inner face of the member 25 at the shank covered with a suitable material to prevent squeaking when the members 25 and 26 are moved in frictional engagement. A piece 27 of frictioned fabric may be employed, or any other suitable substance such as celluloid, sodium silicate or the like may be used.

When the upper and the welt 29 are inseamed to the rib or lip 22, as shown in Figs. 10 and 11, the welt extends uninterruptedly from the heel on one side of the innersole, around the shank and forepart to the heel on the other side. In Fig. 11, which shows a cross section taken at the inside of the shank, the welt and the upper are stitched to the rib or lip 22 on the shank member 26, leaving the other shank member 25 unattached thereto and relatively loose.

In preparing the innersole, after it has been split as described, the heel ends of the shank members may be secured together by stitches, or may be left loose as desired. In any event, however, when the upper is lasted over the face of the innersole at the heel end and is secured in place by tacks or other

fastenings 30, the heel ends of the shank members are permanently secured together. And, in nailing on the heel, the heel-attaching nails may be caused to penetrate the two members 25 and 26. But I should not regard it as a departure from the invention if the heel end of the member 25 were left loose and unattached.

When the shoe is finished and is flexed by the foot of the wearer, in the act of walking, as shown in Fig. 9, the member 25 bends upwardly between its ends and separates from the member 26, thereby rendering the shoe very much more flexible at the shank than would be the case were the innersole solid and unsplit at the shank.

By reason of the construction herein described, I find that the shearing action on the stitches at the juncture of the shank and forepart is materially reduced.

As already stated, in performing the welt-ing or inseam operation, the guide extends into the corner or angle formed by the lip and the face of the innersole, and this corner extends without obstruction to the guide, from one end to the other, from heel to heel around the shank and forepart.

While I have described the process as consisting of certain steps in sequence, it will be apparent that the splitting operation can follow the channeling operation and precede the turning of the lip, this depending on the will of the operator. In fact, the sequence of steps may be otherwise altered, if desired, and the splitting operation may precede the channeling and lip-turning operations. In any such case, it is desirable for some purposes that the channeling knife and the splitting knife shall operate in the same plane, though this is not essential, for other purposes.

Having thus explained the nature of my said invention and described a way of constructing and using the same, although without attempting to set forth all of the forms in which it may be made or all of the modes of its use, what I claim is:

1. A welt shoe having an innersole provided with a continuous rib extending around the shank and the forepart from heel to heel, and an upper and a welt stitched to said rib, said innersole being split at the shank to provide two relatively movable integrally connected layers or members.

2. A welt shoe comprising an innersole having a rib extending around the shank and forepart from heel to heel, and an upper and a welt stitched to said rib from end to end thereof, said innersole being split at its shank into two integrally connected members, the plane of division being approximately coincident with the plane of the juncture of the rib and the feather of the insole.

3. As a new article of manufacture, an in-

- nersole split to provide a supplemental shank member, and having a continuous integral rib extending around the shank and the forepart from heel to heel. 65
5. As a new article of manufacture, an innersole split from one end to provide a supplemental shank member, and having a continuous integral rib extending around the shank and the forepart from heel to heel, said innersole being provided with a rib on the shank member to which the upper may be attached, integral with a rib on the unsplit body portion of the innersole. 70
6. An innersole split between its ends to provide a supplemental shank member, and having a continuously integral rib extending around the shank and the forepart from heel to heel, and means for stiffening or reinforcing said shank member. 75
7. An innersole split between its ends to provide a relatively thin supplemental shank member, and having an integral continuous rib formed partially on the unsplit portion and partially on said supplemental shank member. 80
8. An innersole having a continuous rib extending around the shank and the forepart from heel to heel, said innersole being split from one end to provide integrally connected layers coextensive in length with the shank thereof. 85
9. An innersole split from the heel end to the forepart to provide two shank members, the forepart having a rib for the inseam, and the lower shank member having its side edges turned at an angle to the face thereof and forming extensions or continuations of said rib. 90
10. An innersole having a continuous rib extending around the shank and the forepart from heel to heel, said innersole being split from the heel end to the forepart and being thus provided with relatively movable shank members integrally connected to the forepart thereof. 95
11. An innersole having a continuous rib extending around the shank and the forepart from heel to heel, said innersole being split from the heel end to the forepart and being thus provided with relatively movable shank members integrally connected to the forepart thereof, and a layer of flexible material intervening between said shank members. 100
12. An innersole having a continuous rib extending around the shank and the forepart from heel to heel, said innersole being split from the heel end to the forepart and being thus provided with relatively movable shank members integrally connected to the forepart thereof, and a layer of flexible material adherent to the inner face of one of said members. 105
13. An innersole having a continuous rib extending around the shank and the forepart from heel to heel, said innersole being split from the heel end to the forepart and being thus provided with relatively movable shank members integrally connected to the forepart thereof, and a layer of flexible material adherent to the inner face of one of said members, the confronting faces of said members lying in the plane of the base of said rib. 110
14. An innersole having a continuous rib extending around the shank and the forepart from heel to heel, said innersole being split at the shank in the plane of the angle formed by the feather and the rib, to form two integrally connected shank members. 115
15. A process of making shoes which consists in channeling and turning a lip on an innersole from heel to heel around the forepart, splitting the innersole at the shank thereof, and inseaming the welt and the upper to said lip from end to end thereof. 120
16. The herein described process of preparing an innersole, which consists in channeling and turning a continuous rib from heel to heel and splitting said innersole at the shank to form integrally connected shank members. 125
17. The herein described process of preparing an innersole, which consists in channeling and turning a continuous rib from heel to heel and splitting said innersole from the heel end to the forepart on a plane coincident with the angle formed by the rib and the marginal face of said innersole. 130
18. The herein described process of preparing an innersole, which consists in applying a layer of fabric to the innersole, channeling and turning a lip which extends around the shank and forepart from heel to heel, and splitting the body of the innersole from the heel end to the forepart. 135
19. The herein described process of preparing an innersole, which consists in applying a layer of fabric to the innersole, channeling and turning a lip which extends around the shank and forepart from heel to heel, splitting the body of the innersole from the heel end to the forepart, and then permanently securing the loose heel ends of said split portions together. 140

In testimony whereof I have affixed my signature.

JOHN F. TEEHAN.
